UNITED STATES PATENT OFFICE.

CHARLES S. SAPP, OF RICHARDSON PARK, DELAWARE.

DISHWASHING MACHINE.

Application filed August 19, 1927. Serial No. 214,119.

This invention relates to new and useful improvements in dish washing machines and aims to provide a highly novel simple, but yet efficient machine for domestic use whereby dishes of all characters may be thoroughly washed.

In carrying out the present invention there is provided a semi-circular water pan or basin lined with brushing units while mounted for revolution through the container there are concentric circular series of brushes which rotate on their own axes and that are so correlated with each other and with the brushing units within the container as to cause the complete washing of the dishes that are arranged within the container or first passed through the movable brushes before entering the container.

In the drawings, wherein like numerals refer to like parts throughout,

Figure 1 is a view partially in side elevation and partly in cross section of my improved dish washing machine.

Figure 2 is a top plan view thereof.

Figure 3 is a detail longitudinal section through the water container per se and taken substantially upon the line 3—3 of Figure 2.

Figure 4 is a detail vertical section through the machine taken substantially on the line 4—4 of Figure 1.

Figure 5 is a plan view of the carrier for the revolving and rotating brushes.

Figure 6 is an inner perspective of the brushing unit arranged within the bottom of the container, and,

Figure 7 is a side elevation of one of the revolving and rotating brushes constructed with a flexible shaft for a purpose presently to be described.

Now having particular reference to the drawings my novel dish washing machine consists of a substantially semi-circular metallic container 5 within which is disposed a substantially semi-circular brush head 6 the bristles 7 of which upon the inner face thereof terminate within one edge of the backing or head as clearly disclosed in Figures 4 and 6. Arranged within the side of the container 5 directly above that portion of the brush head 6 that is free of the bristles 7 and resting at its lower edge upon that portion of the backing is a half-moon shaped brush 8 that is secured to the adjacent side wall of the container 5 by screws or the like 9. Obviously, this particular brush 8 will

serve as a means for maintaining the brush 6 in rigid position within the container.

At the ends of the container 5 the side walls thereof are provided with suitable depending supporting legs 10 while rigidly secured to the side wall of the container 5 opposed to the brush unit 8 is a relatively large internal ring gear 11 that extends considerably above the top of the container as clearly disclosed in Figures 1 and 2. Arranged for rotation through the side wall of the container 5 to which the ring gear 11 is secured is a transversely extending shaft 12 the outer end of which is provided with a turning hand crank 13. Keyed to the inner end of this shaft 12 is a circular plate 14 while arranged for rotation through the plate 14 at the outer edge thereof and directly within the ring 11 are a series of inwardly extending brush shafts 15 upon the inner ends of which are arranged circular brushes 16. Also mounted for rotation through this plate 14 around the center thereof are similar inwardly extending horizontal shafts 17 upon the inner ends of which are mounted smaller circular brushes 18. The ends of the brush shafts 15 within the ring gear 11 are equipped with gears 19 that have mesh with the internal teeth of the ring 11 so as the shaft 12 is rotated the brushes will be revolved while at the same time the same will be rotated within their own axes by reason of the gears 19 having mesh with the teeth of the ring gear 11.

Secured to the wall of the container 5 within the center of the ring gear 11 and through which the shaft 12 loosely passes is a gear 20 in mesh with which are smaller gears 21 upon the adjacent ends of the shafts 17 of the inner series of brushes 18, with the obvious result that these brushes will also be rotated during the movement of the same through the container 5.

The relation of the brushes 6 and 8 within the container 5 and the brushes 16 carried by the plate 14 are such that the bristles of said brushes 16 will have wiping engagement with the bristles 7 of the brush head 6 while the forward ends of the brushes 16 as well as the brushes 18 will have engagement with the bristles of the brush 8 at the side wall of the container. Obviously, when water is poured into the container 5 and the handle 13 rotated, dishes may be disposed within the container with the other hand,

and thoroughly cleaned. If desired, small dishes, such as saucers and the like may be arranged between the revolving and rotating brushes before the same are moved into the container, so that a further cleaning action will be brought about by said brushes 16 and 18. Furthermore, cups and other hollow ware, may be arranged directly over the ends of the brushes 16 or 18 above the 10 container and during the turning of these brushes, they will not only be cleaned on the inside, but also on the outside.

In Figure 7 there is disclosed a slightly modified form of one of the movable brush 15 units. This brush unit is similar to the movable brush unit in the other figures, with the exception that the shaft 15' is equipped with a coil spring insert 22 so that the brushes may flex when bulky ware is being 20 washed without bending the shaft or flattening the brush bristles.

It will therefore be seen that I have provided a highly novel, simple and extremely efficient dish washing machine that is well 25 adapted for all of the purposes heretofore designated and even though I have herein shown and described the invention as consisting of certain detailed structural elements, it is nevertheless to be understood 30 that some changes may be made therein without affecting the spirit and scope of the appended claims.

I claim:-

1. In a dish washing machine of the character described, a semi-circular water container open at its top side, a semi-circular brush arranged in the bottom wall of the container, a brush arranged at the inner surface of one side wall of the container, a 35 shaft mounted transversely through the opposite side wall of the container and adapted to be rotated, a circular member keyed to the inner end of the shaft within the container, concentric series of spaced brush 40 shafts mounted for rotation through the circular member, brushes upon the inner ends of said shafts, and means for causing 45

the rotation of the brushes during the movement of the same through the container all in a manner and for a purpose described. 50

2. In a dish washing machine of the character described, a container open at its top side and having a semi-circular bottom wall, a similarly shaped brush arranged within the bottom wall of the container, the bristles of the brush terminating adjacent one edge of the brush head, a second brush arranged upon the inner face of one side wall of the container adjacent the unbristled end of the first mentioned brush head the lower 60 edge of said second mentioned brush resting upon the first mentioned brush head and a series of brushes mounted for circular movement into and out of the container, and means for causing the rotation of the 65 brushes during such movement.

3. In a dish washing machine of the character described, a container open at its top side and having a semi-circular bottom wall, a similarly shaped brush arranged within the bottom wall of the container, the bristles of the brush terminating adjacent one edge of the brush head, a second brush arranged upon the inner face of one side wall of the container adjacent the unbristled end of the first mentioned brush head the lower edge of said second mentioned brush resting upon the first mentioned brush, a series of brushes mounted for circular movement into and out of the container, and means for 70 causing the rotation of the brushes during such movement, said means consisting of a carrier, a plurality of brush shafts arranged for rotation through said carrier, brushes upon the inner ends of said shafts, and means whereby said carrier may be rotated, gear wheels upon the inner ends of said brush shafts and a ring gear anchored to the container in back of said carrier and with the teeth of which said shaft gears 75 80 85 have mesh.

In testimony whereof I affix my signature.

CHARLES S. SAPP.
